CLAIM

The ornamental design for an analysis apparatus, as shown and described.

DESCRIPTION

FIG. 1 is a top and side perspective view of an analysis apparatus showing my new design;

FIG. 2 is a front elevational view thereof;

FIG. 3 is a rear elevational view thereof;

FIG. 4 is a side elevational view thereof from the right of FIG. 3;

FIG. 5 is a side elevational view thereof from the left of FIG. 3; and,

FIG. 6 is a top plan view thereof.

The portions of the design shown in broken lines show unclaimed subject matter.
